UNITED STATES PATENT OFFICE.

WILLIAM KRUTZSCH, OF DAYTON, OHIO, ASSIGNOR TO THE BUCKEYE IRON AND BRASS WORKS, OF SAME PLACE.

APPARATUS FOR PRESSING OIL-CAKES.

SPECIFICATION forming part of Letters Patent No. 296,186, dated April 1, 1884.

Application filed December 3, 1883. (No model.)

To all whom it may concern:

Be it known that I, WILLIAM KRUTZSCH, a citizen of the United States, residing at Dayton, in the county of Montgomery and State 5 of Ohio, have invented new and useful Improvements in Apparatus for Pressing Oil-Cake, of which the following is a specification.

This invention relates to apparatus for shaping and pressing the meal of cotton and other seeds into cakes, and has for its object to provide novel means for effecting the shaping and pressing operations.

To such end the invention consists in a press box or plate capable of sliding upon the ram-block of a ram, combined with brackets or other supports for sustaining the box or plate when slid from the ram-block for permitting the meal to be deposited on said box or plate.

The invention also consists in other features of construction and combination, all of which will be hereinafter described and claimed, reference being had to the accompanying drawings, in which—

Figure 1 is a central vertical section taken from end to end of the apparatus, and illustrating my invention; Fig. 2, a plan view, showing the press box or plate withdrawn from the ram-block; Fig. 3, an end elevation of the same; Fig. 4, a detached elevation of the valve mechanism for controlling the ram; Fig. 5, a sectional plan view taken on the line $x-x$ of Fig. 4; Fig. 6, a top plan view of the casing containing the valve mechanism; and Figs. 7, 8, and 9 are detail views.

Referring to the drawings, A indicates the press-frame of any suitable form, having at its angles or corners the four standards B, having nuts B', which standards and nuts support 40 and hold the head-block C. The press-frame, as shown, is a casting centrally bored out to form an ordinary hydraulic cylinder, D, into which is fitted the ram E, bearing at its top the ram-block M, the ends of which are provided with lateral flanges or shoulders a^2 , that engage grooves at the ends of the press box or plate N, said grooves, as shown, being formed by plates b^2 , bolted or otherwise secured to the shouldered ends c^2 of the box.

To the front side of the press-frame, adj-

cent to the ends, are secured brackets P, the upper horizontal faces of which are so arranged that when the ram is at the limit of its downward stroke the upper surface of the ram-block will be in the same plane as the 55 said faces of the brackets, so that the press box or plate N can be moved outward from the ram-block upon the bracket in position to receive the meal. A sheet-metal tray, e^2 , having a handle, f^2 , is made to closely fit the bottom of the press-box, the rim of the tray being beveled on its inner edge, said tray being thus of dish form; and in the under side of the head-block C is a cavity corresponding to the dish shape of the tray, Fig. 1, so that 60 when the ram is raised the dished cavities will register, forming a chamber, within which the meal is shaped and pressed into a cake.

Adjacent to each end of the press-frame, directly above the brackets P, is a stud, R, to 70 each of which is hinged an end platform, S, which are connected by a rod, T, serving as a handle by which they may be swung up and down. The distance between the two platforms is such that they will just admit the 75 press-box N between them, and their top surfaces, g^2 , are of a form similar to that of the cake to be shaped. The press-box having been withdrawn from the ram-block, to rest upon the brackets P, and the tray arranged 80 thereon, the platforms S are swung down to engage the ends of the tray and hold it in position.

The upper edges, e^2 , of the platforms S, when the latter are in a horizontal position, 85 form trackways or guides continuous with the upper surface or edges of the longitudinal sides of the press-box, on which trackway is adapted to slide a bottomless box, (see dotted lines in Fig. 3,) so that as this box is drawn 90 along the platform from end to end the upper surfaces of the latter constitute a floor or bottom to the box which prevents the meal from falling out of the latter; but in crossing the space between the platforms the meal is deposited on the usual cloth laid on the tray e^2 . The bottomless box is then pushed back upon a stationary track, (not necessary to show,) to be refilled, and the platforms S are swung up to the position shown by dotted lines, Fig. 3, af- 95 100

ter which the two ends of the cloth on the tray are brought up and folded over the meal until they meet or overlap at the center, and the press-box N is then slid in upon the ram-block, the rising of which by hydraulic or other pressure under the ram shapes and presses the meal into a cake between the head-block and the press-box. The meal having been thus shaped and pressed, the ram descends and the press-box is withdrawn upon the brackets for a repetition of the operation.

It will be seen that the longitudinal edge of each platform S is beveled at g^3 , to make its upper surface conform in outline to the shape of the cake to be formed, as before alluded to, and the lower edges of the bottomless box mentioned conform also to this shape in such manner that the top of the meal deposited in the press-box has imparted to it the outline of the completed cake, which is effected by the sliding movement of the bottomless box over the platforms and the press-box.

I will now proceed to describe the valve mechanism by which the ram is controlled.

At one side of the press-frame is arranged a stand, M^2 , in the base of which the valve mechanism is located, being operated by a crank, K, and shaft U through bevel-gears 1 and 2. The inlet a is to be connected with a pump or accumulator, and the passage b leads to the cylinder D, c being the outlet or discharge. The two valves E E' slide back and forth in their respective compartments in the valve-chamber b', and are held to their valve-seats by spiral springs, and the valve-chamber is provided with passages g, to permit the fluid-pressure to reach the top of the valve and hold it tightly to its seat, which passages may, however, be in the valve itself, instead of in the valve-chamber.

To the lower end of a vertical shaft, W, is keyed a cam, G, and to supports L L' are pivoted at f f' two curved levers, H H', provided at their upper free ends with friction-rollers r r', which roll upon the irregular upper surface of the cam G, while the lower free ends of the said levers bear against the outer ends of sliding pins p p', which, at their inner ends, bear against the valves E E', said pins passing through suitable stuffing-boxes. The upper end of the shaft W connects by the bevel-gears 1 2 with the crank-shaft U, and the bevel-gear 2 on the shaft U is provided with just half the number of teeth as the bevel-gear 1 on the shaft W, so that one revolution of the crank-shaft will cause the cam G to perform one-half of a revolution. When the raised or irregular part of this cam is between the rollers r r', both of the valves E E' will be upon their respective seats, and when the raised

part of the cam acts on the roller r, the lever H is tilted, thus pressing in the pin p and moving the valve E from its seat, so that the fluid from the pump or accumulator entering the inlet a flows through the passage b to the cylinder at a point beneath the ram to elevate the latter. If, now, the crank-shaft be once

revolved, the raised part of the cam will leave the roller r and act on the roller r', thus closing the supply-port in the valve-chamber, and by the tilting of the lever H' opening the discharge-port c, thereby permitting the ram to descend.

A receiver, D', in the form of a saucer is arranged under the valve-chamber at the base 75 of the stand M^2 , to catch such liquid as may perhaps escape through the stuffing-boxes of the valve-stems p p'.

It is believed that from the foregoing the operation of all the parts will be clearly understood, and it may also be said that the details in the construction of the various parts may be modified without changing the spirit of the invention.

The ram may be operated by water, oil, 85 steam, gas, or other fluid, as desired.

Having thus described my invention, what I claim is—

1. In an apparatus for pressing oil-cake, a press box or plate capable of sliding upon the 90 ram-block and brackets attached to the frame, substantially as described.

2. In an apparatus for pressing oil-cake, the combination, with a press box or plate capable of sliding upon the ram-block and upon 95 brackets forming a support continuous therewith, of end platforms for engaging with said box or plate, and having their upper surfaces formed to approximate the shape of the upper half of the pressed cake, substantially as de- 100 scribed.

3. The combination, with the press box or plate capable of sliding from the ram-block upon brackets outside the press, of end platforms for engaging the ends of said box or 105 plate, and having their upper surfaces approximating the form of the pressed cake, and a receptacle adapted to traverse said platforms and press box or plate, to deposit the meal upon the latter and shape the upper portion of 110 the mass for the press, substantially as described.

4. The method herein described of pressing oil-cake, said method consisting in laying a cloth upon a press box or plate, depositing 115 the meal thereon, forming the mass into a shape approximating that imparted by the press, folding the two ends of said cloth over thereupon, and submitting the whole to the action of the press, substantially as described. 120

5. The combination of the ram-block having a flange at each end, of the press-plate constructed of such shape as to form the lower half of the cake and having ends which overhang the ram-block, with grooves formed there- 125 in to receive the flanges, substantially as described.

6. The combination, with the press constructed as described, of the end platforms hinged to brackets upon each end of the press, and connected by a rod attached to lugs projecting from the outer ends of said platforms, substantially as specified. 130

7. The combination, with the press having

supporting brackets P P and sliding press-plate N, of the end platforms, S S, formed as set forth and hinged to the studs R R, and the receptacle traversing said end platforms and 5 supplying the meal to and shaping it upon the press-plate, substantially as described.

8. The end platform, S, having a plain top surface, with sides beveled at an angle, $g^o g'$, approximating the form of the upper half of 10 the pressed cake, substantially as described.

In testimony whereof I have hereunto set my hand in the presence of subscribing witnesses.

WILLIAM KRUTZSCH.
